(57) **CLAIM**

I claim the ornamental design for a motorized target practice apparatus, as shown and described.

DESCRIPTION

FIG. 1 is a perspective view of a motorized target practice apparatus showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front elevational view thereof; and,

FIG. 8 is a reduced side elevational view showing the motorized target practice apparatus in use; the broken lines depict environmental structure for illustrative purposes only and form no part of the claimed design.
